(57) **CLAIM**

We claim the ornamental design for a birdfeeder, as shown and described.

DESCRIPTION

FIG. 1 is an isometric view of the birdfeeder showing our new design;

FIG. 2 is a reduced front view in elevation thereof;

FIG. 3 is a reduced right side view in elevation thereof;

FIG. 4 is a reduced left side view in elevation thereof;

FIG. 5 is a reduced back view in elevation thereof;

FIG. 6 is a top plan view thereof; and,

FIG. 7 is a bottom plan thereof.

The broken lines shown in FIGS. 1 through 7 are for illustrative purposes only and form no part of the claimed design.
